ATTORNEY

UNITED STATES PATENT OFFICE.

DANIEL RAYMOND, OF SAN JOSE, CALIFORNIA, ASSIGNOR TO GARDEN CITY POTTERY COMPANY, INC., OF SAN JOSE, CALIFORNIA.

DESIGN FOR A FLOWERPOT.

Application filed December 20, 1921. Serial No. 523,785. Term of patent 14 years.

To all whom it may concern:

Be it known that I, DANIEL RAYMOND, a citizen of the United States, residing in San Jose, county of Santa Clara, State of California, have invented a new, original, and ornamental Design for a Flowerpot, of which the following is a specification, reference being had to the accompanying drawing, forming a part thereof.

The drawing is a front elevation of a flowerpot showing my new design.

I claim:

The ornamental design for a flower pot as shown.

DANIEL RAYMOND.
